UNITED STATES PATENT OFFICE

2,397,173

SHIP PROPULSION TURBINE
ARRANGEMENTGlenn B. Warren, Niskayuna, N. Y., assignor to
General Electric Company, a corporation of
New York

Application April 6, 1942, Serial No. 437,779

4 Claims. (Cl. 60—70)

The present invention relates to ship propulsion turbine arrangements including cruising and high pressure turbines. In arrangements of this kind it is customary during high speed operation to supply high pressure elastic fluid to the high pressure turbine only and during cruising or low speed operation to supply high pressure elastic fluid to the cruising turbine only and to exhaust the fluid discharged from the cruising turbine into the high pressure turbine by means of a crossover conduit, thereby operating the two turbines in series.

During operation of the high pressure turbine with high pressure elastic fluid the cruising turbine is disconnected by means of a valve in the crossover conduit and the exhaust end of the cruising turbine then is connected to a condenser to maintain the cruising turbine under vacuum and thereby to avoid excessive heating of the cruising turbine while idling during operation of the high pressure turbine only. In order to perform these various functions a number of valve mechanisms have to be actuated to change from one operation to the other. The safety of operation may be seriously impaired by faulty operation of such valve mechanisms.

The object of my invention is to provide an improved construction and arrangement of ship propulsion turbine arrangements of the kind above specified whereby faulty operation due to errors by the operator in handling the various valve mechanisms is substantially eliminated. This is accomplished in accordance with my invention by the provision of an improved valve mechanism and means for automatically actuating such mechanism upon change from cruising operation to high pressure turbine or high speed operation and vice versa.

In a preferred embodiment a valve mechanism for connecting the exhaust end of the cruising turbine in one position in series with the high pressure turbine and in another position to a condenser or the like is actuated by a hydraulic motor or differential pressure responsive mechanism controlled by the pressure difference between a lower stage pressure of the cruising turbine and the first stage nozzle pressure of the high pressure turbine.

For a consideration of what I believe to be novel and my invention, attention is directed to the following description and the claims appended thereto in connection with the accompanying drawing.

The single figure of the drawing illustrates a 55

ship propulsion turbine arrangement embodying my invention.

The arrangement shown in the drawing comprises a high pressure turbine 10 with an inlet 12 for receiving high pressure elastic fluid and a plurality of control valves 13 for admitting fluid to several sections of a first turbine stage 14. The various valves in the chest 11 are controlled by a handwheel 15. In addition the arrangement includes a cruising turbine 16 having an inlet chest 17 with control valve means 18 controlled by a handwheel 19. The cruising turbine has a plurality of stages with bucket wheels 20 fastened to a shaft 21. The shafts of the high pressure turbine 10 and the cruising turbine 16 in the ordinary ship propulsion arrangement are connected to drive a ship's propeller through the intermediary of a speed-reducing gearing, not shown.

20 The cruising turbine has an exhaust end disconnected to a conduit 22, which latter may be connected by means of a valve mechanism 23 to either the first stage of the high pressure turbine 10 by means of a conduit 24 or to a condenser 25 by means of a conduit 26. In the position shown the conduit 22 discharges into the conduit 24 and together with the latter forms a crossover conduit between the turbines 10 and 16.

25 The valve mechanism 23 comprises a casing 30 27 which has three chambers, an intermediate chamber 28 having an inlet connected to the conduit 22, a lower chamber 29 for communication with the chamber 28 and having an outlet connected to the conduit 26, and an upper chamber 35 30 for communication with the chamber 28 and with an outlet connected to the conduit 24. The communication between the chambers 28, 29 is controlled by a valve disk 31 and the communication between the chambers 28, 30 is controlled

40 by another valve disk 32. The disks 31 and 32 are secured to a common valve stem 33. In the position shown the disk 31 engages its seat, thus disconnecting the conduit 22 from the condenser while the disk 32 is in its fully opened position, permitting the flow of fluid from the conduit 22 into the conduit 24. The valve mechanism is in this position during cruising operation when the valves 18 of the cruising turbine 16 are open and the inlet valves 13 of the high pressure turbine 10 are closed.

45 The valve mechanism during such operation is automatically moved into and held in the position shown by means of a differential pressure responsive device 34. This device includes a servo-motor having a cylinder 35 with a piston 36 movably

disposed therein and secured to a stem 37, which latter forms a continuation of the valve stem 33. The piston 36 is biased upward by means of a compression spring 38 disposed within an extension 39 of the casing 35 and having an upper end engaging a spring plate 40 secured to an extension 41 of the piston 37. The upper end of the extension 41 engages a screw 42 having an outer end secured to an emergency handwheel to permit manual closing of the valve 32 for high speed operation upon failure of the automatic mechanism. The piston 36 within the casing 35 forms a lower and an upper pressure chamber. The lower chamber underneath the piston 36 is connected by a pipe 43 to a lower stage of the 10 cruising turbine and thereby is subjected to low stage pressure of the latter. The upper chamber above the piston 36 is connected by a pipe 44 to a higher stage, preferably the first stage of the high pressure turbine 10, and thereby is subject to the pressure of the first segment or section of the first stage nozzle. In the position shown the pressure in the upper chamber is low because the valves 13 of the high pressure turbine are 15 closed and the pressure then existing ahead of the first stage of the high pressure turbine is slightly lower than the exhaust pressure of the cruising turbine. The pressure in the lower chamber below the piston 36 in the casing 35 is higher due to the communication of this chamber with the intermediate stage of the cruising turbine. The force exerted by this higher pressure on the piston 36 together with the force of the spring 41 holds the piston in its upper end position in which the valve disk 30 is fully open and the disk 29 is closed. During high speed operation the cruising turbine is shut down by closing of the valves 18 by means of the handwheel 19 and the high pressure turbine valves 13 are 20 opened by means of the handwheel 15. To assure safe operation it is important that the position of the valve disks 31 and 32 is reversed upon opening of the valves 13. This reversing is accomplished automatically because upon the opening of the first valve 13 high pressure is set up in the upper chamber above the piston 36 and the force exerted by this high pressure causes downward movement of the piston 36 against the biasing force of the spring 38 and the force of the pressure existing in the lower chamber below the piston 36. Downward movement of the piston 36 causes closing of the valve disk 32 and opening of the valve disk 29, thereby connecting the exhaust conduit 22 of the cruising turbine to the condenser 25. Vice versa, upon closing of the high pressure turbine valves 13 by the handwheel 15 and opening of the cruising turbine valves 18 by the handwheel 19 the valve disks 31, 32 are moved into the position indicated in the drawing.

Thus, with my invention I have accomplished an improved construction and arrangement of ship propulsion turbines whereby the position of a valve mechanism including a valve for connecting the cruising turbine and the high pressure turbine in series and another valve for connecting the cruising turbine to a condenser is automatically reversed upon change from cruising to high speed operation, and vice versa.

Having described the method of operation of my invention, together with the apparatus which I now consider to represent the best embodiment

thereof, I desire to have it understood that the apparatus shown is only illustrative and that the invention may be carried out by other means.

What I claim as new and desire to secure by Letters Patent of the United States is:

1. Ship propulsion turbine arrangement for cruising and high speed operation comprising a cruising turbine, a high pressure turbine, a condenser, means including a valve mechanism for connecting in one position the turbines in series and for connecting in another position the cruising turbine to the condenser, and means for automatically reversing the position of the valve mechanism in response to change from cruising to high speed operation and vice versa, said means including a device responsive to changes of the pressure difference between a high pressure stage of one turbine and a low pressure stage of the other turbine.

2. Ship propulsion turbine arrangement for cruising and high speed operation comprising a cruising turbine, a high pressure turbine, a condenser, means including a valve mechanism for connecting in one position the turbines in series and for connecting in another position the cruising turbine to the condenser, and means for automatically reversing the position of the valve mechanism upon change from cruising to high speed operation and vice versa, said means including a device responsive to the pressure difference between the pressures in an intermediate stage of the cruising turbine and in a high pressure stage of the high pressure turbine.

3. Ship propulsion turbine arrangement comprising a high pressure turbine having an inlet valve for controlling the flow of high pressure elastic fluid thereto during high speed operation, a cruising turbine having an inlet valve for controlling the flow of high pressure elastic fluid thereto during cruising operation, a crossover conduit for conducting exhaust fluid from the cruising turbine to the high pressure turbine during cruising operation, a valve in the crossover conduit to interrupt communication between the 45 cruising turbine and the high pressure turbine during high speed operation, and means including a device responsive to changes of the inlet pressure of the high pressure turbine for automatically positioning the last named valve upon 50 change from cruising to high speed operation and vice versa.

4. Ship propulsion turbine arrangement comprising a high pressure turbine having an inlet valve for controlling the flow of high pressure elastic fluid thereto during high speed operation, a cruising turbine having an inlet valve for controlling the flow of high pressure elastic fluid thereto during cruising operation, a crossover conduit for conducting exhaust fluid from the 60 cruising turbine to the high pressure turbine during cruising operation, a valve in the crossover conduit to interrupt communication between the cruising turbine and the high pressure turbine during high speed operation, and means for automatically positioning the last named valve upon 65 change from cruising to high speed operation and vice versa, said means including a differential pressure responsive device having two pressure chambers communicating with a lower stage of the 70 cruising turbine and a higher stage of the high pressure turbine respectively.

GLENN B. WARREN.
